UNITED STATES PATENT OFFICE.

JOHN T. BREECE, OF PORTSMOUTH, OHIO.

WOODEN FLOOR.

Application filed February 11, 1926. Serial No. 87,627.

This invention relates to the construction of wooden floors and has for its purpose to effect such an improvement upon the wooden floor constructions heretofore commonly employed as to provide, at a cost less than the cost of an ordinary tongue and groove flooring, a flooring which has superior finish; greater durability; freedom from cracking, curling and warping; freedom 10 from squeaks; and which is air and watertight.

The invention makes use of the fact, which has heretofore been established in the manufacture of high grade pieces of furniture 15 such as table tops, that individual strips of wood may be permanently glued up into a unit structure wherein the strength of the glued joints in relation to the capacity of the wooden strips to expand and contract within 20 themselves under different conditions of moisture and temperature is such that the unity of the structure will not be destroyed, the expansion and contraction being so distributed and controlled that the development 25 of cracks, curling, warping and squeaking is prevented. It is quite possible so to glue together properly cut and properly proportioned pieces of wood that the joints will be stronger than the wood, and from that 30 point of view the improved wooden flooring of the invention may be regarded as a unitary structure in which the glued joints are the strongest sections holding the wooden strips together, while that expansion 35 and contraction which necessarily occurs under varying atmospheric conditions is taken up within the wooden strips themselves without breaking the joints or warping, or cracking the wood.

40 In carrying out the invention, the unitary floor construction is built up of individual flooring strips, properly cut and of proper width and thickness. It has been found that, with reasonable adherence to good mill 45 practice in the choice and application of the glue, flooring strips of the standard widths and thicknesses now commonly employed in good floor construction may be used. For example, one may employ with complete success wooden flooring strips from $\frac{3}{8}$ inch to 50 $\frac{11}{16}$ inch thick and from 1 to 5 inches wide; but it is preferable to increase the thickness of the strips more or less as their width increases. That is, while it is quite 55 satisfactory to employ flooring strips as wide as 2 inches when they are only $\frac{3}{8}$ inch

thick, it is desirable to make a thicker strip if they are to be as much as 4 or 5 inches wide. The object in any case is to establish such a relation between the thickness and 60 the width that the total volume of any strip between the joints will be sufficient to take up the expansion and contraction and consequently the glued joints will hold the floor together without the development of cracks 65 in the portion of the strips lying between the glued joints.

For the purpose of making a glued joint of the desired strength and permanence, the flooring strips are cut with squared edges 70 and preferably without tongues and grooves. The squared meeting edges of the strips afford extended parallel contacting surfaces for the glued joints, and avoid the tendency for the strips to become distorted at the 75 joints, which tendency has heretofore resulted in an uneven surface. Sawed squared edges provide the best surface for the glue. The elimination of the tongues and grooves also reduces the wastage and the cost of 80 manufacture.

The flooring strips having thus been cut, preferably sawed, with squared edges, are built up at the mill into flooring sheets of standard width, and either of standard 85 length or of special length particularly appropriate to the floor into which the sheets are to be built. This building up of the strips into sheets is effected at the mill by gluing the individual strips together in 90 much the way that wooden strips have heretofore been glued together to make table tops or to make cores for veneered table tops, doors, and the like; that is, the glue 95 is properly spread on the squared edges and the strips are then forced into contact 100 with one another and held under pressure, by suitable clamps, or by automatic machinery, until the glue has set. In building up these sheets at the mill, it is possible to have the wood selected and matched by skilled men in any case where that is desirable. A width of 12 inches is a convenient one for these flooring sheets, but it should be understood that the width selected 105 will depend upon such considerations as the size of the whole floor, the convenience of handling, and other circumstances peculiar to the job of laying the floor.

110 It is convenient and desirable, after the flooring sheets have been built up at the mill, to subject them there to processes of

finishing by machinery, or even by hand, thereby eliminating or substantially reducing the tedious and costly finishing operation at the job. The so-constructed flooring sheets are shipped from the mill to the job, and may there be laid by the carpenters, either directly upon the floor joists or upon a sub-flooring, as may be desired, but it is a valuable characteristic of the improved 10 flooring that it lends itself to the cheaper construction of floors in which no sub-flooring is employed, because the completed floor constructed in accordance with the invention will be air and watertight.

15 In laying the floor at the job, the flooring sheets will be laid upon the joists or upon the sub-floor one after the other and secured together by applying glue to the meeting edges of the sheets and then pressing them together. It is found desirable to secure the flooring sheets to the joists or sub-floor by nailing while the meeting edges are still pressed together, but the amount 20 of this nailing may be reduced, as compared with ordinary strip flooring, because 25 of the floor-sheet construction.

This flooring construction lends itself very well to a case in which a border is provided around the floor. In that case the border 30 sections may be made up to specification at the mill with all the effect of a piece of cabinet work, and the space within the border will be filled up at the job by laying in the 35 appropriately cut flooring sheets in the manner already described.

In the accompanying drawing:

40 Fig. 1 is a perspective view of one corner of a room laid with a border within which has been secured in place one flooring sheet made in accordance with this invention, and another flooring sheet ready to be laid in place is shown;

45 Fig. 2 shows two square-edged flooring strips with their adjacent edges glued together.

The drawing illustrates the invention applied to a simple floor construction having a plain central section with a surrounding border. The drawing shows one corner of a 50 room with the border sections in place, one flooring sheet already laid up against the border sections, and a second flooring sheet ready to be laid against the first. Each flooring sheet is composed of a number of 55 wooden strips of uniform thickness and preferably uniform width, though not necessarily so, with the edges sawed at right angles to the surface and devoid of tongue and groove. These edges are permanently 60 secured together by a layer of glue applied at the mill in conjunction with suitable means or apparatus for forcing the strips together and holding them under pressure 65 until the glue has set into permanent joints which will, if a good glue is used, be stronger

than the wood itself. These flooring strips may vary in length as illustrated in the drawing. The sheets made up at the mill will be of standard length or of a length corresponding to the specification of the particular job, and preferably will be completely planed, sanded and finished at the mill so that, when laid into the complete floor, little or no planing, sanding or polishing will be necessary.

A complete floor built up in the manner described has many advantages over the ordinary tongue and groove floor. It effects a substantial saving in cost of manufacture, both by the saving in material resulting 80 from the elimination of the tongue and groove, and by the saving of labor incident to making the tongue and groove. It lends itself to selection of the wood and to the substantial completion of the finishing operation at the mill. The laying of the floor is economical because the work is reduced in proportion to the number of the sheets as compared with the greater number of strips in the ordinary flooring, and this results in a substantial saving of labor. Furthermore, the wider sheets very substantially reduce the difficulty of laying the last portion of the floor which becomes troublesome when narrow strips are used because of the contracted space in which the work must be done. The completed floor is a unit smoothed and polished, with no cracks to receive dirt or moisture; it is air and watertight, will take a perfect 90 finish, will not wrap or crack or develop waviness at the joints and will not squeak.

On the whole, it may be said that the finished flooring has all of those desirable features which have heretofore been the aim 105 of good floor construction, and yet it may be produced and laid at less expense than the present tongue and groove flooring.

I am aware that it has heretofore been proposed to glue together the neighboring edges of ordinary tongued and grooved flooring strips united into flooring sheets by spaced cleats extending transversely of the sheet and to which the individual strips are nailed, the said cleats affording additional means supplementing the glued tongue and groove joints for securing the individual strips together, as well as means for supporting the sections upon and securing them to a sub-floor. I do not claim 110 any such arrangement as that, it having been my experience that it is impossible by the use of glue, with or without nails, to fasten tongued and grooved flooring strips 115 to any support so securely that the floor will not develop waviness and breaks at the joints under changing atmospheric conditions.

I claim:

1. A wooden floor made up of square 120

edged flooring strips running parallel to one another throughout the body of the floor and glued together at their squared edges to form a unitary floor structure in which
5 the glued square-edged joints are sufficient in themselves to hold the flooring strips securely together, the flooring strips being individually of such width and thickness as to take up within the wood between the
10 glued joints the expansion and contraction incident to atmospheric conditions, whereby distortion and breaking of the joints and cracking of the wood between the joints are prevented.
15 2. A wooden flooring sheet adapted for the building up of a unitary floor structure, consisting of a number of square-edged flooring strips running parallel to one another and forming a sheet of substantially greater
20 length than width, the individual strips being glued together at their squared edges

in glued square-edged joints sufficient in themselves to hold the flooring strips securely together, the individual flooring strips being of such width and thickness so 25 as to take up within the wood between the glued joints the expansion and contraction incident to atmospheric conditions, whereby distortion and breaking of the joints and cracking of the wood are prevented. 30

3. A wooden floor made up of flooring strips running parallel to one another throughout the body of the floor, the said strips being glued together at their neighboring edges to form a unitary structure 35 in which the glued joints are sufficient in themselves to hold the flooring strips securely together, and being laid directly on a structural foundation.

In testimony whereof I affix my signature.

JOHN T. BREECE.
